BATCH LOADER FOR DRY-MIX CONCRETE
Royal W. Sims, Salt Lake City, Utah
Application February 10, 1955, Serial No. 487,273
12 Claims. (Cl. 214—2)

This invention relates generally to elevating and loading machinery, and is concerned particularly with providing a practical machine for loading batches of dry-mix concrete into transit mixers.

The supplying of ready-mixed concrete directly to the job has become an important specialty business in the construction industry. Transit mixer trucks are utilized for the purpose, and it is necessary that these be charged with a dry mix of the several ingredients in proper proportions prior to setting off on the journey to the point of delivery.

The machine of this invention is adapted primarily for enabling a pre-mixed, dry batch of the material going into the concrete to be conveniently and expeditiously handled during the introduction of same into a transit mixer, it being realized that the feed orifice of the latter is ordinarily located high above ground level.

It is one of the objects of the invention to provide for accurately weighing successive batches of the dry mix prior to introduction thereof into the transit mixer, thereby insuring a proper wet mix.

Another object is to provide for the use of a broadly open transfer container for the batch of dry-mix concrete to be loaded, and for the maintaining of such container in substantially horizontal position during much of the elevating thereof, so that the dry-mix may be conveniently deposited therein from a variety of types of equipment, including customary dump trucks.

Outstanding structural features of the batch loader of the invention reside in the system of levers employed for elevating the transfer container from an initial, horizontally disposed, weighing position, up to a moderately tilted, dump position, and, finally, to a steeply tilted, dump position, and in the winch-operated rigging system employed in conjunction with and as actuating means for the lever system.

An additional object of the invention is to so construct the loader that it can be easily transported from place to place for the performance of its loading function. This is accomplished by providing retractable wheels on the structural supporting base of the machine.

Further objects and features of the invention will become apparent from the following detailed description of that preferred specific construction which is illustrated, by way of example, in the accompanying drawings.

In the drawings:

Fig. 1 represents a side elevation of the batch loader in non-operating, transport condition, the transfer container being in a position which corresponds with its initial, load-weighing position (not otherwise shown) when the transport chassis is in the wheel-retracted, fixed operating condition of Fig. 5;

Fig. 2, a top plan, the rigging not being shown in detail;

Fig. 3, a front elevation;

Fig. 4, a transverse section taken on the line 4—4 of Fig. 1;

Fig. 5, a view corresponding to that of Fig. 1, but showing the loader in non-transport, operating condition, with its transfer container loaded and partially elevated;

Fig. 6, a view corresponding to that of Fig. 5, but illustrating the transfer container in a moderately tilted, dump position, at an advanced stage of elevation, during which the principal dumping of contents into a transit mixer is accomplished;

2

Fig. 7, a similar view, but illustrating the transfer container steeply tilted to an extreme dumping position, which terminates the elevating phase of the operation;

Fig. 8, a top plan corresponding to Fig. 2, but greatly enlarged and with transfer container removed to reveal operating parts including the rigging in detail;

Fig. 9, a fragmentary view in vertical section taken on the line 9—9 and illustrating parts of a standard platform scale mechanism in operating condition, the non-operating, transport condition being illustrated in dotted lines and the entire view being drawn to a scale enlarged over that of Fig. 8;

Fig. 10, a similar view taken on the line 10—10 of Fig. 8 and drawn to a somewhat larger scale, illustrating details of the pivotal connection between certain of the lifting levers or frame and the transfer container;

Fig. 11, a front elevation corresponding to that of Fig. 3, but illustrating a somewhat different construction employing a single cable rigging arrangement, the view being drawn to an enlarged scale and intermediate portions of the structural framework being broken out for convenience of illustration;

Fig. 12, a fragmentary vertical section taken on the line 12—12 of Fig. 11 and drawn to a larger scale;

Fig. 13, a horizontal section taken on the line 13—13 of Fig. 11 and drawn to the larger scale of Fig. 12, intermediate portions being broken out for convenience of illustration;

Fig. 14, a fragmentary view in vertical section taken on the line 14—14 of Fig. 11 and illustrating in detail an optional automatic gas feed cut-off for the engine, advanced positions of the lifting levers or frame and of the gas throttle lever being indicated by dotted lines;

Fig. 15, a view corresponding largely to that of Fig. 14, but illustrating an advantageous arrangement for raising the bedded machine and extending the retracted road wheels, for transport, by the power of the descending transfer container; and

Fig. 16, a similar view showing the machine raised and the retractable road wheels locked in extended, transport position.

Referring to the drawings:

The machine of the invention embodies a rigid structural framework having a heavy base frame or chassis, which is advantageously of rectangular formation, as here illustrated and designated 10. The structural framework also includes upright structure rigidly secured to the base frame and rising to approximately the height at which the elevated load is dumped, so as to provide for mounting of parts of the winch-operated rigging system. In the form illustrated, such upright structure is provided by uprights or columns 11 rising from securement, as by welding, to one end of the base frame 10 at respectively opposite sides thereof. Diagonal braces 12 hold such uprights 11 firmly in position.

For the purpose of making the machine readily transportable from place to place, a pair of road wheels 14 are retractably mounted intermediate the length of the base frame 10, as by means of respective levers 15 pivoted at 16 to respective opposite side members of such base frame, and operable by preferably hydraulic actuated mechanism of any suitable well known type (not shown). A tongue arrangement 18 at the other end of the base frame provides a hitch 19 for attachment to any suitable tractor unit for haulage purposes.

A container adapted to have material dumped thereinto directly from conventional dump trucks for transfer to a transit mixer is securely mounted on the rearward portion of the base frame 10, for elevation to dumping position at the forward end of the latter and above the uprights 11, and, preferably, for weighing the received material prior to elevating it to dumping position. To these

ends, the transfer container simulates the body of a conventional dump truck as commonly used to haul sand and gravel, that is, it does insofar as its normal load-receiving position and general configuration are concerned.

In the illustrated form of the machine, a dump container 20 of rectangular configuration and extending horizontally in the normal load-receiving position of Fig. 1, is broadly open over its top, see Fig. 2, to facilitate discharge thereinto of a charge of previously prepared dry-mix concrete components by the customary dumping operation of a conventional dump truck of the type previously mentioned, as ordinarily used for hauling such components from the dry-mixing plant.

In some instances, it may be desirable to charge the transfer container directly from discharge hoppers of a dry-mixing plant. The container 20 is applicable to such an operation, as well as it is to being charged from a haulage truck.

Such transfer container 20 is mounted rigidly on a supporting frame 21, which is itself mounted and rigged for elevation while remaining in approximately a horizontal plane. The container is thus carried upwardly in approximately horizontal position to approximately the height of the uprights 11.

For this purpose, one end of a lifting frame 22 is pivotally connected, as at 23, to the upright end of the structural framework, while the opposite end is pivotally connected, as at 24, to the adjacent end of the container-supporting frame 21.

A second and longer lifting frame 25 has one end pivotally connected, as at 26, to the upright end of the structural framework, preferably below and in backwardly spaced relation to the first lifting frame 22, and its opposite end pivotally connected to the remote end of the container-supporting frame 21 by a lost-motion connection to be described.

The two frames thus form a four-point suspension system at each lateral side of the apparatus, the two systems being arranged to work in parallel in elevating the container-supporting frame 21 and the transfer container 20 through successive horizontal planes.

In order to properly dump the container at the termination of its upward travel, it is necessary that its end 20a, remote from the upright structure 11, be raised relative to its discharge end 20b, so that the dump container will slope steeply in a downward direction above such upright structure. To this end, the horizontal distance 27, Fig. 5, extending between the pivot connections of the respective lifting frames 22 and 23 at the upright end of the structural framework, is considerably shorter than the corresponding distance 28 between the pivot connections at the opposite ends of the respective pairs of levers considered when the container is in any horizontal position, the relative distances being desirably selected to commence the tipping of the container just before it is raised above the level of the top of the upright structure, though the point at which tipping is commenced being largely a matter of choice.

For bringing the transfer container 20 into steeply sloping position, the pivotal connection of lifting frame 25 with container-supporting frame 21 is made by passing lifting frame end member 25a, Figs. 2 and 8, through elongate slots 29 provided in respectively opposite, longitudinal, side members of the frame 21. Such lifting frame member 25a is normally disposed at the remote ends of these slots, leaving the lengths thereof ready to accommodate it as the container is brought into its steepest, discharge position. For this purpose, the member 25a should be of cylindrical formation, and is preferably a rotatable shaft.

The dumping or discharge end 20b of the transfer container is preferably of convergent hopper formation, as shown, normally closed by a door 30 arranged to be swung open and closed by suitable remotely controlled means, such as the hydraulically controlled mechanism 31.

Lifting of the loaded transfer container 20 from its lowermost or load-weighing position to its final discharge position and lowering of the empty container following discharge of the load are preferably accomplished by means of a rigging system involving a plurality of pulley wheels, wrapping connectors therefor, and a power-operated winch arrangement.

In the construction of Figs. 1-8, the rigging system is made up of two similar and structurally independent sections at respectively opposite lateral sides of the apparatus. Such sections correspond to the respective lever-suspension systems provided by the lifting frames 22 and 25.

Each rigging section comprises a winch drum 32, and a set of pulley wheels, as follows (see Fig. 8): a double pulley wheel 33 rotatably mounted on a shaft 34 which is fixed to and extends between the tops of the respective uprights 11 in mounting brackets 35, a double pulley wheel 36 rotatably mounted on a stub shaft 37 which projects laterally and outwardly from near the rear end of the forward lifting frame 22, a single pulley wheel 38 rotatably mounted on end frame member 25a, and a single pulley wheel 39 rotatably mounted on a stub shaft which projects outwardly from lifting frame 22 adjacent to and forwardly of stub shaft 37. A steel cable 40 extends from attachment to the winch drum 32, over one of the cable ways of double pulley wheel 33, under one of the cable ways of double pulley wheel 36, around pulley wheel 38, back under the other cable way of double pulley wheel 36, around the other cable way of double pulley wheel 33, back around pulley wheel 39, and back to a fixed anchorage to the structural framework, preferably the upright structure 11.

The several pulleys may be regarded as longitudinal cable guides, for they serve to guide the cable in its extension longitudinally of the machine.

The two winch drums are preferably fixed to respectively opposite ends of a common drive shaft 42, which is driven by an engine 43 through any suitable drive, such as the worm gearing 44. Thus, such drums rotate in common, and produce identical actuation of the working parts of the apparatus at respectively opposite sides thereof through the respective rigging cables 40. Any suitable transmission (not shown) may be provided between the engine 43 and drive gearing 44 to make available different drive ratios and reverse drive for the winch.

In operation, following the dumping of transit concrete mix components into the transfer container 20 at its lowermost receiving position of Fig. 1 and with the structural framework firmly bedded as shown in Fig. 5, the engine 43 is thrown into operating relationship with the drive 44 by suitable clutch means (not shown) and utilizing an appropriate drive ratio, the winch being thereby motivated to raise the transfer container to discharge position with respect to a transit concrete mixer (not shown), usually of conventional type. It can be seen that the base frame 10 has a level bottom for the purpose of firmly bedding the machine on any suitable supporting surface, such as level ground, during operation.

Operation of the winch and the resultant winding of the cables 40 on the respective winch drums 32 act, through the rigging system, to raise the lifting frames 22 and 25 simultaneously, thereby elevating the transfer container 20 through successive horizontal planes, from its lowermost position of Fig. 1 through the intermediate raised position of Fig. 5 to the point where lifting frame 22 abuts shaft 34 or some other suitable stop member provided on the uprights 11. From that point on, the continuing forward movement of lifting frame 25 relative to the now stationary lifting frame 22 pushes the rearward portion of the transfer container forwardly and upwardly in an arc about pivot axis 24 as a center.

Immediately prior to or during the latter container-tipping stage, discharge gate 30 is opened by the exercise of manual or automatic control of gate-operating mechanism 31, as may be provided for in any given installa-

tion. Suitable control means of known type may be employed for the purpose. It forms no part of the present invention.

Discharge of material from the transfer container will take place from the time of opening of gate 30 until such material is completely discharged.

For the purpose of insuring complete and rapid discharge, provision is made for moving the transfer container to an extreme tilted position, indicated in Fig. 7. In the illustrated construction, the slots 29 constitute such provision, but any other arrangement for accommodating limited forward movement of the pivotally connected rear end of the rearward lifting frame 25 may be employed. Thus, as the lifting frame 25 is swung forwardly from approximately the position shown in Fig. 6 to that shown in Fig. 7, the slots 29 accommodate the necessary arcuate travel of the rearward portion of the container-supporting frame 21 around the fixed pivot center 24, so far as the pivotal securing of such lifting frame 25 to such container-supporting frame 21 is concerned. The steepness of tipping of the transfer container is determined by the length of the slots 29.

Where found necessary or desirable in the handling of certain materials, vibrator means 46 of any suitable type may be operatively installed with respect to the container, usually against the bottom thereof as indicated.

Following complete discharge of the contents of the transfer container, or so much thereof as may be desired in any given instance, the container is lowered to its initial load-receiving position, utilizing either the reverse drive of the transmission or customary winch braking mechanism (not shown), or both, to retard its gravity descent.

For weighing component materials separately deposited in the transfer container or any pre-mixed charge of same, so as to accurately control the mixing operation in the transit mixer and predetermine the quantity of the final product, a scale is incorporated in the apparatus.

As illustrated, see particularly Figs. 4, 8, and 9, a scale platform 50 is floatingly supported upon the base frame 10 by a conventional system of weighing beams, levers, and knife edges usual for a platform scale of standard type. No attempt is made to illustrate such system in its entirety, but its installation is indicated by so much as is shown. Thus, speaking generally, it is carried by knife points 52, which are supported by extensions 10a of the base frame 10. A lever 53 transmits an accurate measure of the entire load to a considerably longer lever 54, which is fulcrumed at 55 and connected to a scale 56 (Figs. 1, 2, and 8) by means of a rod 57. As illustrated, the lever 53 extends through a tubular entryway 58 into engagement with the lever 54, which is housed within and extends along one of the longitudinal side members of base frame 10 (see Fig. 9).

An important feature of the invention resides in the provision made for effectively freeing the transfer container from its lifting mechanism while at rest on the scale platform 50, so that weighing will be accurate.

As shown in Fig. 10, the pivotal connections 24 of the rear end of forward lifting frame 22 with the supporting frame 21 of the transfer container 20 are made by means of respective pivot pins 60, which are dimensioned to fit snugly within the downwardly directed narrow necks 61a of pear-shaped bushings 61.

During rest of the transfer container on the scale platform, the pivot pins 60 float freely in the enlarged upper portions 61b of the bushings 61, as shown. While such transfer container is being elevated by the lifting frames under the influence of the rigging or hoisting system described above, the pivot pins slip easily and automatically into the narrow journaling necks 61a, and remain there under the influence of gravity during the entire operation. Also, widths of slots 29 freely float member 25a.

For firmly securing such weighing mechanism against

damage during transit of the machine from one location to another, provision is made for clamping the weighing mechanism in its full weight position and for firmly tying down the transfer container to the base frame.

To these ends, a retaining screw 62 is threaded into the tubular casing 58 immediately above the lever 53 and near its free end, as shown in Fig. 4, and a turnbuckle 63 is interposed in the rod 57 leading to the scale. Also, short hold-down chains 64, at opposite side of the machine have one end anchored to the base frame 10 and the opposite end provided with a hook for engaging an eye 65 projecting outwardly from securing to the transfer container. Such chains are each preferably provided with a manually operable cincher of well known eccentric type, as indicated.

In preparing for transit, turnbuckle 63 is manipulated to elongate rod 57, retaining screw 62 is cinched down until lever 54 assumes the dotted line position of Fig. 9, and hold-down chains 64 are hooked into place with respect to their eyes 65, as shown in Fig. 1. The apparatus can now be hitched to and hauled behind a tractive vehicle without damage, it being understood that road wheels 14 are extended into running position for this purpose.

It has been found in practice, that, while the two cable rigging system of the foregoing construction is satisfactory in operation, it is often necessary to expend considerable time equalizing the lengths of the two cables. This difficulty is avoided by the single cable rigging system of the embodiment shown in Figs. 11 through 14.

There, the uprights 11 are surmounted by a structural cross-piece 70, having channel extensions 70a welded to its opposite ends. Gusset plates 71 serve to rigidly interconnect cross-piece 70 with the respective uprights.

Double cable way pulleys 33 are journaled within the respective channel formations 70a, preferably on ball bearings. The remainder of the rigging system corresponds exactly with the previous embodiment, except for the fact that the single cable 72 traverses the width of the upright structure at 72a. There is no anchoring of the cable to the structural framework, as with the pair of cables of the previous embodiment. The two opposite ends of cable 72 are attached to the respective winch drums 32, as shown. Thus, the two sections of the rigging system at respectively opposite sides of the machine are self-adjusting.

The cable 72 passes from one lateral side of the machine to the other by way of transverse cable guides, here shown in the form of arcuate slideways 73 secured at respectively opposite sides of the machine by welding to the opposing inside faces of uprights 11. Longitudinal cable guides 74 of similar slideway type are similarly disposed below the transverse cable guides 73.

In this embodiment, provision is made for automatically cutting down the feed of gas to the engine as the forward lifting frame 22 reaches the end of its lifting stroke. As illustrated in Figs. 11 and 14, gas feed is controlled by means of a lever 75 pivoted to the rearward face of one of the uprights 11 so as to project into the space between the two uprights and into the path of movement of lifting frame 22.

Such gas feed lever is manually advanced by the operator to the point shown by full lines in Fig. 14, for bringing the engine up to working speed. No further attention is required, for, when lifting frame 22 is raised to that point, as indicated by the broken line positions in Fig. 14, further travel thereof will gradually push gas feed lever closed, until idling position is reached when lifting frame 22 abuts against rearwardly projecting stops 76, Figs. 11 and 12.

This embodiment is also provided with means for utilizing descent of the lifting frames to "jack" up the entire machine for transport when desired.

For this purpose, a pair of stands 80, Figs. 15 and 16,

are provided for respectively opposite sides of the machine, to serve as fulcrums for the opposite longitudinal side members, respectively, of lifting frame 25. For convenience, they may be pivotally secured, respectively, to the inside faces of opposite longitudinal side members of the base frame 10, as by means of sliding pin 81 and slot 82 connections, permitting out of the way placement on bracket supports 83 when not in use (see broken line positions).

Recessed fittings 84 are welded to the undersides of the respective longitudinal side members of lifting frame 25 for secure engagement with the tops of stands 80 during the "jacking" operation, as shown.

With this construction, no special equipment is necessary for retracting and extending the road wheels 14. Such wheels are journaled in and carried by lever plates 15, which are, in turn, pivotally secured at 16 to the base frame 10, all as in the previous embodiment. Here, however, threaded openings 85 and 86 are provided in each lever plate and longitudinal base frame side member, respectively, for receiving a locking bolt 87, Fig. 16, when the wheels are extended and such openings are brought into registry.

The stands 80 are removed from operating position after the road wheels have been locked in extended, road-engaging position as above described. Following transportation of the machine to a new working location, it is firmly bedded for operation by spotting it over a suitable level surface, and placing the stands 80 in the supporting position of Fig. 16. After manually unlocking the road wheels by removing the bolts 87, the machine is gradually lowered by operation thereof to raise the lifting frames.

Whereas this invention is here illustrated and described with respect to presently preferred embodiments thereof, it should be understood that various changes may be made from time to time without departing from the teachings hereof or the scope of the claims which here follow.

I claim:

1. A batch loader, comprising a rigid structural framework made up of a base frame adapted to accommodate a forwardly dumping type of transfer container, and upright structure rising from the forward portion of said base frame to a height approximating dump height; an elongate, forward, lifting frame; an elongate, rearward, lifting frame, said frames each being aligned longitudinally with said base frame and pivotally connected at their forward ends to said structural framework at a low level adjacent said upright structure; an elongate, forwardly dumping type of transfer container assembly arranged to normally occupy the rearward portion of said base frame in longitudinal alignment therewith, the rear end of said forward lifting frame being pivotally connected to the forward end portion of said transfer container assembly, and the rear end of said rearward lifting frame being pivotally connected to the rear end portion of said transfer container assembly; means associated with said transfer container assembly accommodating limited forward movement of the said pivotally connected rear end of the rearward lifting frame; a rigging system for elevating the transfer container assembly, said system including a winch having a cable winding drum, a cable attached to the winch drum, cable guide means including a cable guide secured to the rear end portion of said rearward lifting frame and a cable guide at a high point on said upright structure, the said cable being looped about the first cable guide and over the second; and means for operating said winch.

2. A batch loader as set forth in claim 1, wherein a scale platform is carried by the rearward portion of the base frame for directly receiving and supporting the transfer container in its lowermost position; wherein weighing mechanism is carried by the structural framework; and wherein means are provided operably inter-

connecting said scale platform with said weighing mechanism.

3. A batch loader as set forth in claim 2, wherein the base frame is in the form of a vehicle chassis; wherein running gear is secured to said base frame, adapting the batch loader for travel; wherein means are provided for immobilizing the weighing mechanism; and wherein means are provided on said base frame for anchoring the transfer container relative to the scale platform for purposes of travel.

4. A batch loader as set forth in claim 1, wherein the base frame is in the form of a vehicle chassis having a level bottom adapted to bed firmly upon a supporting surface; and wherein road wheels are retractably mounted in said base frame, adapting the batch loader for travel.

5. A batch loader as set forth in claim 4, wherein stands are provided as fulcrums for one of the lifting frames in exerting leverage to raise the machine; and wherein means are provided for locking the road wheels in extended, road-engaging position.

6. A batch loader as set forth in claim 1, wherein the transfer container is of rectangular configuration, having broad bottom and broad open top extending horizontally in the lowermost, load-receiving position; and wherein dump means are provided at the forward end of said container.

7. A batch loader as set forth in claim 6, wherein the forward end of the transfer container is of convergent, hopper formation.

8. A batch loader as set forth in claim 1, wherein the rigging system embodies independent cables at opposite lateral sides of the lifting frames; wherein the cable guide means include longitudinal cable guides secured to respectively opposite lateral sides of the rearward lifting frame; and wherein the winch drum has portions operatively aligned with the respective cables.

9. A batch loader as set forth in claim 1, wherein the rigging system embodies a single cable comprehending opposite lateral sides of the lifting frames; and wherein the cable guide means include longitudinal cable guides secured to respectively opposite lateral sides of the rearward lifting frame, and sets of longitudinal and transverse cable guides secured to the upper part of the upright structure, the said single cable passing from one lateral side of the loader to the other by way of said transverse cable guides.

10. A batch loader as set forth in claim 1, wherein a scale platform is carried by the rearward portion of the base frame for directly receiving and supporting the transfer container in its lowermost position; wherein weighing mechanism is carried by the structural framework; wherein means are provided operably interconnecting said scale platform with said weighing mechanism; and wherein a free-floating, pivotal connection pivotally connects one of the lifting frames to the transfer container assembly.

11. A batch loader as set forth in claim 10, wherein the free-floating, pivotal connection pivotally connects the forward lifting frame to the transfer container assembly, and comprises a generally pear-shaped bushing having its larger end uppermost in the normal rest position of the transfer container assembly, and a pivot pin snugly fitting and rotatable within the smaller, neck end of said bushing.

12. A batch loader as set forth in claim 1, wherein the means for operating the winch includes a fuel-consuming engine equipped with a fuel supply line and fuel supply control means interposed therein; and wherein an operating handle for said control means is positioned within the path of lift of the forward lifting frame adjacent the termination of its lifting stroke, for forward closing movement within and along said path.
